UNITED STATES PATENT OFFICE.

ANDREW C. WOLFE, OF FREEPORT, PENNSYLVANIA, ASSIGNOR OF ONE-THIRD TO JOSEPH M. HEWITT, OF ALLEGHENY, PENNSYLVANIA.

RAILWAY-SWITCH MECHANISM.

SPECIFICATION forming part of Letters Patent No. 678,084, dated July 9, 1901.

Application filed February 27, 1900. Serial No. 6,684. (No model.)

To all whom it may concern:

Be it known that I, ANDREW C. WOLFE, a citizen of the United States, residing at Freeport, in the county of Armstrong and State 5 of Pennsylvania, have invented or discovered new and useful Improvements in Railway-Switch Mechanism, of which the following is a specification.

In the accompanying drawings, which make 10 part of this specification, Figure 1 is a plan view of a section of a street-railway equipped with my device. Fig. 2 is a vertical section of the floor of the car provided with the pushing mechanism which engages with the switch- 15 throwing mechanism in the street. Fig. 3 is a section on line III III of Fig. 1. Fig. 4 is a section on line IV IV of Fig. 1. Fig. 5 is a side elevation of what I call the "power-box" and its inclosing dirt-box; Fig. 6, a horizontal section through Fig. 5 on line VI VI; Fig. 7, a vertical section on line VII VII of Fig. 5.

The purpose of my invention, generally stated, is mechanism for throwing switches, 25 and more particularly street-railway switches, by means which shall be powerful and simple.

In the accompanying drawings, which make 30 part of this specification, A A are the rails of the main track.

B B are the rails for the branch track. C is a switch-tongue, which is connected by a system of levers D, E, F F, and G G with screw-wedges H H. These levers are preferably covered by an iron plate I, which spans 35 the track from wheel to wheel; but they can be arranged and protected in any desired manner. The lever G in both cases is suitably secured in the side of the screw-wedges H H, preferably threaded therein, as shown 40 in Fig. 6. The screw-wedge H travels in what I term the "power-box" K. It is threaded to match the threads on the screw-wedge H. The power box or bearing K is slotted at k to permit of the movement of the lever G, as is also the dirt box or shield L at E' for the same purpose. The dirt-shield L is provided with a cap l², which rests upon the upper end 45 of the screw-wedge H and is provided with two downwardly - depending flanges E³ E³, which make a neat working fit on the sides of the power-box K. One of these flanges is

slotted at l⁴ to permit of the movement of the lever G. The inclination of the threads h h on the screw-wedge is sufficiently close to parallelism with the longitudinal axis of the 55 screw-wedge that an end thrust on said screw-wedge will cause the same to move in its box by a rotary progressive movement.

M is a push in the floor N of the car and is pivoted in bracket O. In frictional contact with the same is the lever P, pivoted in the bracket Q and bearing at its lower end a depressing-wheel R. The lower end of lever P is normally held up with the spring S. The floor-push M in cars which are designed to go 60 on the main line would be located to engage the screw-wedge on one side of the track, and the floor-push on cars which are going on the branch line would be located on the other side of the car to engage the screw-wedge on 65 the other side of the track. In the drawings the screw-wedge for the main line is shown at the right-hand side for the outgoing car and on the left side for the outgoing car on the branch line. Obviously the reverse sides 70 could be chosen. On the return trips of both cars the car-wheel flanges return the switch to its position in the usual manner.

The operation of the apparatus is as follows: As the car approaches the switch the 80 motorman tramps on the push M, which depresses the wheel R, which is located in alignment with the cap l², which is pressed down upon the upper edge of the screw-wedge H, throwing the same down and rotating said 85 screw-wedge, which turns lever G and by the connected system of levers throws the switch. Obviously as one screw-wedge is depressed the other will be raised.

Various changes can be made in the details 90 of the mechanism described, but still embodying the main features of my invention. For instance, any system of levers could be adopted between the screw-wedge and the switch-tongue. The dirt-box can be omitted and the 95 depressing mechanism on the car be brought into immediate contact with the end of the screw-wedge, if desired. Any convenient motor mechanism also between the car and the screw-wedge may be substituted for the two 100 levers and the wheel which I have illustrated.

Having described my invention, I claim—

1. The combination of a screw-wedge; a bearing for the same; a railway-switch; connections between said screw-wedge and said railway-switch and means carried by a car for moving said screw-wedge.
2. The combination of a screw-wedge; a bearing for the same; a railway-switch; connections between said screw-wedge and said railway-switch and means carried by said car for imparting an end thrust to said screw-wedge.
3. The combination of a screw-wedge having threads of such inclination that the application of power on the screw-wedge will move the same; a bearing for said screw-wedge; a railway-switch; connection between said railway-switch and said screw-wedge and means carried by the car to impart an end thrust to said screw-wedge.
4. The combination of a screw-wedge; a bearing for said wedge; a cap moving upon said bearing and in contact with the end of the said screw-wedge; a railway-switch; connection between said screw-wedge and said
- 5 railway-switch and means carried by the car 25 to push against the cap for the bearing.
5. The combination of a screw-wedge; a bearing for said wedge; a dirt-shield inclosing said bearing; a cap for said dirt-shield; said cap being in contact with the end of said screw-wedge; a railway-switch; a connection between said screw-wedge and said switch and means carried upon the car to impart a push to said cap.
6. The combination of a railway-switch; a 35 system of levers leading from said switch to two screw-wedges oppositely located; bearings for said screw-wedges and means carried by the car simultaneously depressing one screw-wedge and raising the other screw- 40 wedge.

Signed at Pittsburg, Pennsylvania, this 17th day of February, 1900.

ANDREW C. WOLFE.
